[57] **CLAIM**

The ornamental design for a combined casserole with
reversible cover, substantially as is shown.

DESCRIPTION

FIG. 1 is a front perspective view of a combined casse-
role with reversible cover showing our new design;

FIG. 2 is a top plan view thereof;

FIG. 3 is a rear elevational view thereof;

FIG. 4 is a side elevational view thereof;

FIG. 5 is a bottom plan view thereof;

FIG. 6 is an exploded front perspective view thereof;

FIG. 7 is a top plan view of the base portion of the
casserole; and

FIG. 8 is a bottom plan view of the reversible cover.
